Ursula B. Day(57) **CLAIM**

The ornamental design for an operator cabin, as shown and described.

DESCRIPTION

FIG. 1 is a perspective front and left side view of an operator cabin showing my new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is rear elevational vie thereof.

The broken lines in FIG. 6 are included for the purpose of illustrating portions of the operator cabin that form no part of the claimed design.
